UNITED STATES PATENT OFFICE.

ELMER E. THEIS, OF DAYTON, OHIO.

PERMUTATION SWITCH-LOCK.

1,115,130.

Specification of Letters Patent. Patented Oct. 27, 1914.

Application filed February 9, 1914. Serial No. 817,389.

To all whom it may concern:

Be it known that I, ELMER E. THEIS, a citizen of the United States, residing at Dayton, in the county of Montgomery and State of Ohio, have invented certain new and useful Improvements in Permutation Switch-Locks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in switch locks to be used in connection with the ignition circuits of automobiles.

20 The principal object of the invention is to provide a switch lock that may be utilized to lock the electrical ignition system of all makes of automobiles, thereby greatly extending its utility.

25 A further object is to provide a simple and compact switch lock which is easily manipulated and comprises comparatively few parts all of which are supported upon the face plate of the lock housing.

30 To the foregoing ends my invention consists of the parts hereinafter described and claimed.

Referring more particularly to the drawings, Figure 1 is a rear elevation of the device showing the casing in section; Fig. 2 is a top plan sectional view partially diagrammatic, showing the switch connected into the well known form of ignition circuit; and Fig. 3 is a front elevation of the complete

40 lock.

In the specification and drawings, similar reference characters indicate corresponding parts.

The lock may be mounted on any suitable part of the automobile, preferably the dash 1, a portion of which is shown in Fig. 1, provided with a suitable pocket which receives the casing 2 with face plate 3. The face plate 3 supports the entire mechanism 45 of the lock and the same may be conveniently removed and therewith the said lock mechanism. The said face plate is provided with bosses 4 forming bearings for shafts 5. Drums 6 are mounted on the shafts 5 inside

the casings 2, while the finger knobs 7 of 55 the shafts lie in front of the face plate in a convenient position for operation. The drums 6 are given the necessary rotation from the knobs 7. In the present instance the drums 6 are made of metal and are, 60 therefore, conductors of electricity. The said drums being of metal, the device is adapted to operate on the closed circuit principle. Brushes 8 and 9 are mounted on suitable insulated supports 10 extending 65 from the face plate 3 and engaging said drums. When the said brushes are in contact with the drums, the ignition circuit, hereinafter described, will be grounded thereby preventing its operation. To eliminate the ground connections of the ignition circuit, the drums 6 are provided with insulated blocks 11 mounted in their peripheries. When the said brushes are in contact with the insulated blocks 11, the ground connection is broken and the ignition circuit is operative. To indicate when the brushes 8 and 9 are in contact with said blocks 11, the drums 6 are provided with peripheral notches 12 in which the ends 13 of the 75 brushes are adapted to snap. The open circuit position of the blocks 11 is thus ascertained by the number of clicks of the brushes 8 and 9 when the drums 6 are moved from normal positions by the knobs 7. The normal positions of said drums are indicated by feeling through the agency of stop pins 14 mounted on the face plate 3 and pins 15 mounted on the drums. The 80 number of clicks necessary to move the drums in order to bring the blocks 11 in engagement with the brushes 8 and 9 may be changed by setting the pins 15 in any of a number of openings 16 in said drums. In the present instance, I have shown three 85 such drums and it is necessary, owing to the electrical connections, to bring all of the insulated blocks 11 in contact with the brushes before the ground circuit will be opened. Consequently, three numbers, one 90 for each drum, must be known to the operator before he can successfully manipulate the lock. It is contemplated that these numbers will only be known to the owner or driver of the automobile thereby preventing 95 the machine being operated by unauthorized persons. The drums 6 are held in their set 100 positions by the ends 13 of the brushes rest-

ing in the notches 12 but brake-springs 17 may be provided, said springs being mounted between the face plate 3 and the drums 6.

In the present instance, I have shown the lock as connected into a well known type of ignition system which system is known in the art as the "Bosch dual system". This system is shown diagrammatically in the lower portion of Fig. 2 in which 18 represents the ground or frame of the automobile, 19 the battery, 20 the coil, 21 the spark-plug, 22 the distributor and 23 the battery timer. The lead wire 24 runs from the battery circuit breaker, while the lead wire 25 is the magneto ground wire. As is well known, if either of these wires are grounded, the circuit becomes inoperative. This expedient is accomplished in my invention through the agency of lead wires 26 which are connected to the lead wire 25 and in parallel to the brushes 8. The lead wire 26 grounds the magneto circuit, while the battery circuit is grounded through lead wires 27 which connect into the battery wire 24 and in parallel into the brushes 9. It will, therefore, be seen that in thus constructing a lock, the ignition circuit will be grounded and inoperative except only when all of the drums 6 are properly set and the ground circuits are broken by the insulated blocks 11. In completing the ground circuit through the switch the switch casing is grounded through the agency of a lead wire 28. It will be noted that the brushes 8 are for the battery, while brushes 9 are for the magneto. It will, therefore, be seen that

when a single system is used, either battery or magneto, only one set of brushes will be necessary.

Having described my invention, I claim.

1. In an electric switch, a series of metallic drums each having a series of concentric apertures, an insulating member mounted in the periphery of each of said drums, brushes arranged to engage the drums and the insulating members thereon, pins adapted to be set in the concentric apertures of said drums to limit the rotation thereof, and stops arranged in the paths of said pins to arrest the movement imparted to said drums. 40

2. In an electric switch lock, the combination with the face plate of the lock casting, having a series of laterally extended apertured bosses, of a series of drums mounted on shafts extending through said apertured bosses, each of said drums having its periphery serrated and concentric openings in the sides thereof, a setting pin adapted to be inserted in said openings, an insulated block set in the periphery of each drum, brushes arranged to engage the periphery of each drum, and stops arranged in the path of each setting pin to arrest the rotation of the drums in the operation of said drums. 45

In testimony whereof I affix my signature, in presence of two witnesses.

ELMER E. THEIS.
